UNITED STATES PATENT OFFICE

WILLIS P. THOMAS, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Original application filed November 6, 1922, Serial No. 599,330. Divided and this application filed November 25, 1929. Serial No. 409,611.

This invention relates to boiler cleaners and has particular reference to a boiler cleaner of the type in which a blower element discharges jets of cleaning fluid adjacent the portions of the boiler to be cleaned.

The invention numbers among its objects the provision of means for adjusting the blower element to adjust the jets of cleaning fluid discharged by the same relative to the portions of the boiler to be cleaned; the provision of an adjusting means of this character which will permit the adjustment of the blower element and the head which supplies cleaning fluid to the blower element relative to the wall of the boiler to be cleaned; and the provision of adjusting means of this character which will be readily accessible from a point exteriorly of the boiler whereby the blower element may be readily adjusted to take care of any changes in the relation between the blower element and the boiler incident to operation of the boiler.

Other objects and advantages of the invention will become more apparent as the following description proceeds, particularly when reference is had to the accompanying drawing.

This application is a division of my co-pending application, Serial No. 599,330, filed November 6, 1922.

In the drawing,

Figure 1 is a vertical sectional view, partly in elevation, of a blower unit constructed in accordance with the teachings of this invention, and

Figure 2 is an end view of the unit shown in Figure 1.

Referring then particularly to the drawing wherein like reference characters designate corresponding parts throughout all views, the numeral 10 designates generally a boiler, which includes the boiler tubes 11 and the boiler wall 12. The numeral 13 designates a rotatable blower mounted therein and connected by a coupling 14 to a swivel tube 15 journaled in the head 16.

This head includes a flanged goose-neck 17 which at its lower end is secured to a flange 18 on the stationary inlet pipe 19.

To provide a certain degree of resiliency, the pipe 19 is preferably provided with the bend 20 which yields sufficiently to permit a limited movement of the head 16.

The flow of cleaning fluid from the pipe 19 to the blower element is controlled by a valve 21 which seats against a valve seat 22 and is normally held against its seat by a valve spring 23. A trigger 24 pivoted as at 25 to a bracket 26 carried by the goose-neck is adapted to engage the stem 27 of the valve 21 to open the same against the tension of the spring 23, and this trigger is actuated by a cam 28 fixed for rotation with the blower element 13.

The blower element 13 extends through a wall box 30 mounted in an opening 31 in the boiler wall and is supported by clamps 32 from the boiler tubes. A plate 33 seals the opening between the outer periphery of the blower element and the inner periphery of the wall box, and this plate is normally held against the wall box flange 34 by means of a spring 35.

To prevent the entire weight of the blower head being carried by the inlet pipe and the boiler tubes, there is provided a cap screw 40 fixed to the flange 34 of the wall box and extending through slots 41 in a floater cap 42. Housed within this floater cap is a spring 43 which at its lower end abuts against the screw 40 and at its upper end, against a retaining disk 44, the position of which may be adjusted by a set screw 45. The floater cap carries the sealing plate 33 which is loosely sleeved upon the blower element and thus through the swivel tube carries the head 16.

For adjustably spacing the blower head from the boiler wall, there is provided a stud 50, fixed as at 51 to the flange 34 of the wall box. This stud extends through a slot 52 formed in a bracket 53, and this bracket is secured at its lower end as by a cap screw 54 and at its upper end by a tie rod 55 to the head 16. As illustrated, the slot 52 is preferably considerably larger in diameter than the stud 50, whereby the bracket and the head fixed to the same may move freely in the plane of the boiler wall but are pre-

vented from movement transversely thereof. A washer 56 engages the bracket 53 and is in turn engaged by a nut 57 threaded on the end of the stud 50 for determining the position of the head 16 relative to the wall 12.

It will be obvious that by adjustment of the nut 57 on the stud 50, the bracket 53 and the head 16 may be adjusted toward or away from the boiler wall 12. It will also be obvious that adjustment of the head 16 toward or away from the wall 12 will effect a longitudinal adjustment of the blower element 13 to position the nozzles 58 thereof relative to the boiler tubes 4. Thus the blower element may be adjusted to take care of shifts in the positions of the tubes relative to the wall, slight permanent changes in the length of the blower element and other changes of this character which are incidental to the use of the boiler.

It will be noted that in the construction as described, the head 16, as well as the blower element, has a spring or yielding support from the boiler wall and is thus in reality carried by the boiler wall while still being free to move relative thereto. The bent portion 20 of the pipe 19 provides for floating of the head 16 relative to the boiler wall and provides also for the movement of the blower head and blower element incident to adjustment of the nut 57 on the stud 50.

From the above it is believed that the structure of the invention, as well as the operation thereof, will be clearly apparent. The blower element and the blower head are both supported from the boiler wall but are mounted for movement relative thereto, as will be readily apparent. The blower head is adjustably connected to the boiler wall and may therefore be adjusted relative to the boiler wall to adjust the location of the blower element relative to the portions of the boiler to be cleaned. The cleaner element may therefore be adjusted to provide for any changes in the relation of the boiler parts to the cleaner unit parts incident to the operation of the boiler, and this adjustment may be made from a point exteriorly of the boiler.

For the sake of convenience the invention has been described as being embodied in a device for cleaning boilers. It will be apparent, however, that the invention may be embodied in devices for cleaning apparatuses similar to boilers, and it is to be therefore understood that the term "boiler" wherever used in the specification or claims is to be construed as meaning a heat transfer apparatus or fluid heater of any character, while the term "boiler cleaner" is to be construed as meaning a cleaner for any such apparatus.

While the invention has been described with considerable detail, it is to be clearly

understood that the description is for the purposes of illustration only and is not definitive of the limits of the inventive idea. The right is therefore reserved to make such changes in the details of construction and arrangement of parts as will fall within the purview of the attached claims.

What I claim as my invention is:

1. In a boiler cleaner, the combination with a boiler wall, a blower element projecting through said wall for discharging jets of cleaning fluid adjacent the portions of the boiler to be cleaned, and a head arranged exteriorly of said boiler wall for supplying cleaning fluid to said blower element, said blower element being rotatable relative to said head but fixed against longitudinal movement with respect thereto, of means for adjusting said blower element relative to the portions of the boiler to be cleaned, said means including a bracket fixed to said head and a member fixed to said boiler wall and adjustably engaging said bracket.

2. In a boiler cleaner, the combination with a boiler wall, a blower element projecting through said wall for discharging jets of cleaning fluid adjacent the portions of the boiler to be cleaned, and a head arranged exteriorly of said boiler wall for supplying cleaning fluid to said blower element, said blower element being rotatable relative to said head but fixed against longitudinal movement with respect thereto, of means for adjusting said blower element relative to the portions of the boiler to be cleaned, said means including a bracket fixed to said head, and means for adjustably spacing said bracket from said boiler wall.

3. In a boiler cleaner, the combination with a boiler wall, a blower element projecting through said wall for discharging jets of cleaning fluid adjacent the portions of the boiler to be cleaned, and a head arranged exteriorly of said boiler wall for supplying cleaning fluid to said blower element, said blower element being rotatable relative to said head but fixed against longitudinal movement with respect thereto, of means for adjusting said blower element relative to the portions of the boiler to be cleaned, said means including a bracket fixed to said head, a stud fixed relative to said boiler wall and passing through an opening in said bracket, and a member adjustably mounted on said stud and engaging said bracket.

4. In a boiler cleaner, the combination with a boiler wall, a blower element projecting through said wall for discharging jets of cleaning fluid adjacent the portions of the boiler to be cleaned, and a head arranged exteriorly of said boiler wall for supplying cleaning fluid to said blower element, said blower element being rotatable relative to said head but fixed against longitudinal movement with respect thereto, of means for

adjusting said blower element relative to the portions of the boiler to be cleaned, said means including a bracket fixed to said head, a stud fixed to said boiler wall and projecting outwardly from the same, and a member threaded on said stud and engaging said bracket.

5. In a boiler cleaner construction, the combination with a tubular boiler and a furnace wall for said boiler provided with an aperture, of a soot blower comprising a blower head and a blower member journaled in said blower head, the blower member having a portion passing through the aperture in said wall with clearance therein, said blower head being fixed against movement transversely of the furnace wall, said blower member being mounted upon and adapted to move with the tubular boiler, means for 10 yieldably supporting the outer end of said blower member, said means comprising a plate adapted to seal the aperture around the blower member, and a spring coiled about said blower member for holding said 15 plate in sealing position.

6. In a boiler cleaner, the combination with a boiler wall, and a nozzled blower element projecting through an opening in said wall and permanently located in a position 20 where it extends transversely of spaced portions of the boiler to be cleaned with its discharge nozzles definitely positioned with reference to the said spaced portions to be cleaned, of means for adjusting said blower 25 element in a direction transversely of said boiler portions to compensate for changes incident to operation of the boiler in the original positions of the nozzles thereof with reference to the said portions of the boiler to 30 be cleaned.

7. In a boiler cleaner, the combination with a plurality of boiler tubes, a boiler wall, and a nozzled blower element projecting through an opening in said wall and 35 permanently located in a position where it extends transversely of said boiler tubes with its discharge nozzles definitely positioned with reference to the spaces between said boiler tubes, of means for adjusting said 40 blower element in a direction transversely of said boiler tubes to compensate for changes incident to the operation of the boiler in the original positions of the nozzles thereof with reference to the spaces between said 45 boiler tubes.

8. In a boiler cleaner, the combination with a plurality of boiler tubes, a boiler wall, a nozzled blower element projecting through an opening in said wall and 50 permanently located in a position where it extends transversely of said boiler tubes with its discharge nozzles definitely positioned with reference to the spaces between said 55 boiler tubes, and a fitting disposed exteriorly of the boiler wall for supplying clean-

ing fluid to the blower element, of means for adjusting said fitting in such a direction as to effect an adjustment of said blower element in a direction transversely of said boiler tubes to compensate for changes incident to the operation of the boiler in the original positions of the nozzles thereof with reference to the spaces between said 70 boiler tubes.

9. In a boiler cleaner, the combination with a plurality of boiler tubes, a boiler wall, a blower element projecting through said boiler wall and extending transversely of said boiler tubes, means for supporting said blower element from said boiler tubes, 75 nozzles on said blower element spaced longitudinally thereof and accurately located with reference to the spaces between the boiler tubes, and a blower head disposed exteriorly of the boiler in which the blower 80 element is rotatably journaled, of means for adjustably positioning said blower head in such a direction as to effect an adjustment of the blower element in a direction transversely of said boiler tubes to compensate 85 for changes incident to the operation of the boiler in the original positions of the nozzles of the blower element with reference to the spaces between the boiler tubes.

In testimony whereof I affix my signature. 90
